UNITED STATES PATENT OFFICE.

ERNEST M. MOORE AND PAUL J. TIMBERLAKE, OF JACKSON, MICHIGAN, ASSIGNORS TO
IRA A. JONES COMPANY, OF CHICAGO, ILLINOIS, A COPARTNERSHIP.

DESIGN FOR A STAND OR HOLDER FOR CUT FLOWERS AND PLANTS.

40,361.

Specification for Design.

Patented Nov. 16, 1909.

Application filed July 9, 1909. Serial No. 506,858. Term of patent $3\frac{1}{2}$ years.

To all whom it may concern:

Be it known that we, ERNEST M. MOORE and PAUL J. TIMBERLAKE, citizens of the United States, residing at Jackson, in the county of Jackson and State of Michigan, have invented a new, original, and ornamental Design for Stands or Holders for Cut Flowers and Plants, of which the following is a specification, reference being had to the accompanying drawing, forming a part thereof.

The drawing is a perspective view of a stand or holder made according to our new design.

What we claim is:

The ornamental design for a stand or holder for cut flowers and plants as shown.

ERNEST M. MOORE.
PAUL J. TIMBERLAKE.
